[57] CLAIM

The ornamental design for a wrap-around panty or similar article, as shown and described.

DESCRIPTION

FIG. 1 is a plan view of a wrap-around panty or similar article showing my new design in flattened condition;
FIG. 2 is a front elevational view of my new design as it is worn upon a body;

FIG. 3 is a rear elevational view thereof;

FIG. 4 is a side elevational view thereof; and

FIG. 5 is an elevational side elevational view of the opposite side with the ties unjoined.
